Primary Examiner—Doris Clark*Assistant Examiner*—Michael Pratt(74) *Attorney, Agent, or Firm*—Levisohn Berger LLP(57) **CLAIM**

The ornamental design for a combined bracelet or ring jewelry linkage, described in the drawings.

DESCRIPTION

FIG. 1 is a perspective view of a first embodiment of the present invention;

FIG. 2 is a top plan view of the invention of FIG. 1;

FIG. 3 is a bottom plan view of the invention of FIG. 1;

FIG. 4 is a right side plan view of the invention of FIG. 1, the left side plan view being substantially identical; and,

FIG. 5 is a top plan view of a second embodiment of the present invention, the remaining views being substantially identical with those of the first embodiment except for proportional relationships.

The broken lines are for illustrative purposes only and form no part of the claimed design.
